US00D862793S

(12) **United States Design Patent** (10) Patent No.: **US D862,793 S**
Chang et al. (45) Date of Patent: ** Oct. 8, 2019

(54) **AEROSOL GENERATING DEVICE**

(71) Applicant: **PHILIP MORRIS PRODUCTS S.A.**,
Neuchatel (CH)

(72) Inventors: **Wei Chia Chang**, Geneva (CH);
Jeffrey Tung, San Francisco, CA (US);
Hankak Lee, Seoul (KR)

(73) Assignee: **Philip Morris Products S.A.**,
Neuchatel (CH)

(**) Term: **15 Years**

(21) Appl. No.: **35/504,614**

(22) Filed: **Sep. 14, 2017**

(80) **Hague Agreement Data**

Int. Filing Date: **Sep. 14, 2017**
Int. Reg. No.: **DM/097854**
Int. Reg. Date: **Sep. 14, 2017**
Int. Reg. Pub. Date: **Mar. 16, 2018**

(30) **Foreign Application Priority Data**

Mar. 14, 2017 (EM) 003800051-0003
Mar. 14, 2017 (EM) 003800051-0004
(Continued)

(51) **LOC (12) Cl.** 27-02

(52) **U.S. Cl.** **D27/162**
USPC D27/100, 101, 162-170, 172-195

(58) **Field of Classification Search**
USPC D27/100, 101, 162-170, 172-195

Primary Examiner — Khawaja Anwar

(74) *Attorney, Agent, or Firm* — Oblon, McClelland, Maler & Neustadt, L.L.P.

(57) **CLAIM**

The ornamental design for an aerosol generating device, as shown and described.

DESCRIPTION

1.-3. Aerosol generating device

1.1 perspective view;
1.2 front view;
1.3 rear view;
1.4 right side view;
1.5 left side view;
1.6 top plan view;
1.7 bottom perspective view;
1.8 bottom plan view;
1.9 top perspective view;
2.1 perspective view;
2.2 front view;
2.3 rear view;
2.4 right side view;
2.5 left side view;
2.6 top plan view;
2.7 bottom plan view;
2.8 top perspective view;
3.1 perspective view;
3.2 front view;
3.3 rear view;
3.4 left side view;

(Continued)

- 3.5 right side view;
 3.6 top plan view;
 3.7 bottom plan view;
 3.8 another perspective view.

1 Claim, 25 Drawing Sheets
